GARMENT

Ruth M. Kapinas, Minneapolis, Minn., assignor,
by mesne assignments, to Munsingwear, Inc.,
Minneapolis, Minn., a corporation of Delaware

Application February 4, 1935, Serial No. 4,904

3 Claims. (Cl. 2—36)

The garment of the present invention is of the corset or girdle type of a construction now well known, namely of that type which is made of so-called two-way stretch material.

Garments of the type referred to now upon the market do not fully and satisfactorily perform their expected function of properly controlling the figure of the wearer in all postures. It is particularly noted that with such garments, when the wearer is sitting, the diaphragm and stomach are allowed to somewhat protrude and thus spoil the flat effect which is so highly desirable. In such posture or in any other posture similar thereto, the fact that the garment is made of material which stretches in both directions permits the rounding and projecting of the diaphragm and stomach out of the flat position desired. On the other hand, if the garment were not made of such stretchable material it will not be as comfortable as the wearer desires.

The particular object of my invention is to provide a garment of the character described which is made of stretchable material and which is provided with means for maintaining the diaphragm and stomach of the wearer flat in all usual postures of the body.

Another object of the invention is to provide a garment of the character described with an inelastic insert adapted to cover the diaphragm and upper part of the stomach of the wearer, but which does not extend to the top edge of the garment but leaves the top edge free to conform to the figure.

Other objects of the invention and the advantages thereof will more fully appear as the description proceeds.

In order to illustrate a practical embodiment of the invention, I have appended hereto drawings showing a practical construction of the garment. It is understood, however, that my invention is not limited to the details of construction shown in these drawings. It will be apparent to those skilled in the art that the principle of the invention is susceptible of embodiment in a variety of forms without sacrificing any of the advantages thereof and without departing from the scope of the invention as defined in the appended claims.

50 In the drawings

Figure 1 is a front view of the inside of a garment embodying my invention;

Figure 2 is a fragmentary front view similar to Figure 1 with the inelastic insert shown in dotted lines;

Figure 3 is a detail front view showing the construction of the inelastic insert;

Figure 4 is a front view of the garment on the person; and

Figure 5 is a perspective view showing the garment on a wearer in sitting posture and illustrating particularly the effect of the garment on the diaphragm and stomach.

Referring now to the drawings, reference numeral 10 indicates, in general, the body portion of the garment. As above indicated, the body portion may be made of the material now well known as two-way stretch material. However, any other suitable material may be employed. Also, the garment may be made in the form of a single 15 seamless tube or it may be made of several sections of material suitably secured together. It will be understood that so far as the general construction of the body of the garment is concerned, this may be of any desired form.

The top edge of the garment is suitably bound by means of a tape 11 extending therearound and which tape may be made of any suitable material, desirably elastic so that it may conform to the stretching of the garment and not prevent such stretching.

On either side of the center line of the front of the garment may be provided suitable bones 12 of any desired material secured to the body of the garment in any desired manner.

Reference numeral 13 indicates, generally, a relatively inelastic insert which is secured, as by stitching 14, to the inside of the front of the garment. As will be seen from the drawings, this insert 13 is secured to the garment along its vertical edges and the bottom edge but is free therefrom at the top. This insert may be made of any woven material such as silk or satin or any other material suitable and desirable for the purpose. It will be noted that the insert does not 40 extend to the very top edge of the garment but on the other hand, terminates a slight distance therebelow. To relieve the upper elastic area of the garment above the inelastic insert and the upper portions of the lines of stitching 14 of 45 severe strain when pulling the garment onto the body, suitable tapes 15, preferably of elastic material, are shown loosely connecting the upper corners of the inelastic insert to the edge tape 11. The tapes 15 serve to distribute a portion of 50 the pulling strain exerted on the upper area of the garment, when pulling it on, to the insert 13 below the elastic upper area, and thus relieve the upper area and the stitching of excessive strains.

As will be seen more particularly from Figure 3, 55

the vertical edges of the said inelastic insert 13 are provided with bone pockets in which are housed suitable bones 16. The material in construction of such bones may be any of those well known and generally used in garments of this general character.

Along the center line of the garment and beneath the said inelastic insert 13, I have provided a longitudinally extending bone pocket 17 containing a bone 18. As will be seen from Figures 1 and 2, this bone is in no way connected with the inelastic insert 13, but the pocket 17 loosely overlies the said bone. The bone 18 extends to the very top edge of the garment and is concealed by the tape 11.

The foregoing, I believe, will make the nature of my invention clear to those skilled in the art. The purpose of said inelastic insert 13 is to maintain the diaphragm and upper stomach of the wearer flat by preventing the transverse or horizontal stretching of the garment. Moreover, the provision of the bones in the pockets 14 along the edge of the insert will serve to make this part of the garment vertically semi-rigid. With only the center bone 18 extending to the edge of the garment, the transverse or circumferential stretching of the top edge of the garment is permitted. As will be seen more particularly from an inspection of Figure 5, the said center bone 18 extends upwardly into the flat space between the breasts of the wearer but does not prevent a slight forward as well as transverse bending of the garment.

Figure 5 shows the effect of my construction upon the figure of the wearer when in sitting posture. By this construction, it will be seen that the diaphragm and stomach of the wearer are maintained flat, thus accomplishing the very desirable object of garments of this general type.

40 I claim as my invention:

1. A garment of the character described comprising a body portion of elastic material, a diaphragm engaging insert of inelastic fabric at the center of the front of said body portion and terminating short of the top edge thereof, and being bordered above by an area of elastic material of the body portion, means loosely connecting said insert to the top of the garment, and a bone secured to the center of the body portion under said inelastic insert and extending upwardly through said area of the body portion to the top edge of the garment.

2. A garment of the character described comprising a tubular body portion of elastic fabric, a diaphragm engaging reinforcing panel of rela-

tively inelastic fabric extending lengthwise of the front of the garment, said panel being secured thereto at its opposite side edges along vertical lines located between the front center line and the respective side areas of the garment and being bordered on each side by elastic areas of the body portion, the reinforcing panel terminating short of the top of the garment and being bordered above by an elastic fabric area of the body portion adapted to engage the region immediately 10 below the busts, said panel terminating short of the lower end of the garment and being bordered below by a hip engaging elastic tubular area of the body portion, a vertical stiffening bone opposing but free of connection with the reinforcing 15 panel secured to the body portion at its front center line, said center bone having an upper portion extending upwardly above the reinforcing panel through the elastic upper area of the body portion to the top of the garment and being 20 adapted to engage the region between the busts of the wearer, said center bone at its lower end terminating short of the lower end of the garment and being bordered below by the elastic tubular hip engaging area of the body portion. 25

3. A garment of the character described comprising a seamless tubular body portion of elastic fabric, a diaphragm engaging reinforcing panel of relatively inelastic fabric providing an additional thickness of material in the diaphragm 30 area of the body portion, said reinforcing panel being secured along its opposite side edges to the front of the body portion and being bordered at each side edge by an elastic area of the body portion, the reinforcing panel terminating short 35 of the top of the garment and being bordered above by an elastic fabric area of the body portion adapted to engage the region of the wearer immediately below the busts, said panel terminating short of the lower area of the garment and being bordered below by a wide elastic tubular hip engaging area of the body portion, a pair of spaced stiffening bones secured to the reinforcing panel adjacent its respective side edges, and terminating at its upper ends short of the 40 elastic area above the reinforcing panel, and a center stiffening bone opposing but free of connection with the reinforcing panel secured along the vertical center line of the body portion, said center bone having an upper portion extending 45 above the reinforcing panel and the other stiffening bones to the top of the garment and adapted to engage the regions between the busts of the wearer. 50
